UNITED STATES PATENT OFFICE.

NATHANIEL B. WALES, OF NEW YORK, N. Y., ASSIGNOR TO RICHARD D. WARD, OF NEW YORK, N. Y.

CLOSURE FOR CONTAINERS.

1,326,885.

Specification of Letters Patent.

Patented Dec. 30, 1919.

Application filed May 9, 1919. Serial No. 295,974.

To all whom it may concern:

Be it known that I, NATHANIEL B. WALES, a citizen of the United States, residing at New York, in the county of New York and 5 State of New York, have invented certain new and useful Improvements in Closures for Containers, of which the following is a specification.

This invention relates to closure caps for 10 bottles, jars, tubes or similar containers and its main object is to provide an effective sealing device which may be readily applied or removed by mere pressure of the fingers.

The closure is made of metal celluloid or 15 other suitable material which possesses sufficient resiliency to permit of a certain amount of distortion so that it may be sprung out of normal shape to loosen the securing tongues, lips or lugs from the rim 20 or flange of the vessel or container and will immediately resume its shape when pressure is removed.

I have illustrated the different forms of 25 my invention in the accompanying drawings, in which Figure 1 is a side elevation of a jar or bottle having my closure applied thereto; Fig. 2 is a side elevation of the same turned at an angle of 90°; Figs. 3 and 4 are vertical sectional views on the line 30 A—A of Fig. 2 showing the closure in locked and unlocked positions respectively; Figs. 5 and 6 are horizontal sectional views of the closure in normal and distorted positions respectively; Figs. 7 and 8 are corresponding views of a modified form of 35 closure; Fig. 9 is a vertical sectional view of a jar or container showing a closure of the type illustrated in Figs. 7 and 8 in unlocked or distorted position; Fig. 10 is a 40 fragmentary side elevation of a jar provided with a screw top and showing my closure applied thereto; and Fig. 11 is a plan view of the blank from which the closure is formed.

45 My closure member or sealing cap is adapted for use upon bottles, jars, or tubular containers of any of the ordinary constructions in which the neck portion or top is provided with an annular flange or rib 50 or with an indentation, socket or recess to provide a ledge to receive the securing tongues or lips or gripping fingers of the closure cap.

I have shown a jar 1, having an annular 55 recess or groove providing a ledge 2 which

may be gripped by the tongues 5 of the closure caps 6.

The closure members are formed of metal or other suitable resilient material and are preferably first stamped or cut from a sheet 60 into the blank form shown in Fig. 11, with the oppositely disposed lugs 5 between which are cut the arcuate or segmental slits 7. The blank is then stamped into the form shown in Figs. 1 and 2, in which the downwardly 65 turned flange is provided with a reinforcing expanded annular bead or rib 8 below the slots 7 and from which the tongues 5 depend and deflect inwardly.

The function of the slots 7 upon opposite 70 sides of the flange is to sever the rib portion 8 therebelow from the disk top part so that it may freely yield to lateral pressure. In the form illustrated in Figs. 1 to 6, the flange portion of the closure member is normally 75 circular in outline as indicated in Fig. 5. By pressing with the fingers against the sides of the ribs or beads 8 midway between the tongues 5, said sides will move inwardly from the position indicated in broken lines in 80 Fig. 6 to that shown in full lines, the annular rib 8 becoming ovate in section. To accommodate this movement the uncut end portion must bulge outwardly and as the part adjacent the flat disk cannot yield, the 85 tongues 5 must rotate or swing outwardly, the lower free edges making the greatest movement.

When the sides are pressed inwardly as indicated in Fig. 6, the tongues 5 are separated 90 sufficiently to permit the cap to be slipped over the top of the jar or bottle as indicated in Fig. 4, and upon releasing the pressure the flange will spring back into the normal shape indicated in Fig. 5. In this 95 position, the tongues 5 take under the ledges 2 of the jar top and lock the cap thereon. The parts may be so designed that the edges of the lips or tongues will strike the upper 100 inwardly inclined sides of ledges 2 so that the resiliency of the metal will exert a downward tendency and hold the cap tight upon the rim or mouth of the jar. For the purpose of insuring a more perfect seal, a gasket or packing washer 9 may be interposed between 105 the jar top and the inner side of the cap. This washer may be constructed of cork or other suitable impervious material and thus constitute an inner resilient sealing lining of the cap. This gasket or seal- 110

ing disk may also serve to seal the slits 7 in the flange of the cap.

For certain purposes it may be desired to provide a greater range of movement of the 5 clamping tongues and of the actuating elements of the flange 8. This may be accomplished by upsetting the metal slightly at the ends of each actuating flange portion or element, viz: at those parts directly below the termini of the slots as indicated at the points α , α in Fig. 7, the actuating portion, which is severed from the top disk by the slots, being given a permanent bulge outwardly. The greater range of movement is 10 indicated in Fig. 8 in which the broken lines indicate the normal position of the parts and the full lines the distorted or unlocked positions. This construction necessarily increases the spring action of the clamp. The 15 greater distance which the tongues will be moved is also indicated in Fig. 9, in which the tongues are in unlocked position.

In Fig. 10, I have shown the clamping tongues 5 obliquely arranged at such an 20 angle that they will fit over or mesh with and conform to the threads of a jar having a screw top or neck. Other changes and 25 modifications within the spirit of my invention will readily appear to engineers and

those who understand the principles of my 30 closure cap as above described.

I claim:—

1. A closure cap for receptacles, comprising a disk having a depending flange provided with oppositely arranged clamping 35 tongues, and the portions between the tongues being provided with circumferentially extending slits.

2. A closure cap for receptacles, comprising a flat disk having a depending flange 40 provided with a plurality of clamping tongues diametrically arranged, the intermediate portion of the flange being spaced from the receptacle and yieldable, whereby the tongues will move outwardly in opposite 45 directions when said intermediate flange portions are pressed inwardly.

3. A closure cap for receptacles, comprising a disk having a depending flange provided with oppositely arranged clamping 50 tongues, and the portions between the tongues being provided with circumferentially extending slits, the part below the slits having an annular bead or rib formed 55 therein.

In testimony whereof I affix my signature.

NATHANIEL B. WALES.
